(57) **CLAIM**

The ornamental design for a vagina-shaped computer mouse, as shown and described.

DESCRIPTION

FIG. 1 is a top view of a vagina-shaped computer mouse showing my new design with simulated pubic hair; FIG. 2 is a top view of a vagina-shaped computer mouse showing my new design without hair;

FIG. 3 is a top view of my new design depicting use in a human hand;

FIG. 4 is a bottom view thereof;

FIG. 5 is a front elevational view thereof;

FIG. 6 is a rear elevational view thereof;

FIG. 7 is a left side elevational view thereof; and,

FIG. 8 is a perspective view thereof.

The broken lines are for illustrative purposes only and form no part of the claimed design.
